MAGNETO ELECTRIC GENERATOR

Filed Nov. 22, 1929

FIG. 1

UNITED STATES PATENT OFFICE

HENRY G. COX, OF BELOIT, WISCONSIN, ASSIGNOR TO FAIRBANKS, MORSE & CO., OF CHICAGO, ILLINOIS, A CORPORATION OF ILLINOIS

MAGNETO-ELECTRIC GENERATOR

Application filed November 22, 1929. Serial No. 409,035.

This invention relates to improvements in magneto-electric generators such as are employed for igniting combustible mixtures in the cylinders of internal combustion engines.

5 An object of the present invention is to provide an improved magneto in which is embodied means for rendering certain mechanical parts of the device inoperative during certain portions of the armature rotation, in order to prevent generation of unused electrical impulses, whereby to minimize wear and deterioration of the parts of the device.

A further object is to provide simple and effective means for readily and easily varying the angular relation between the breaker device and the breaker actuating cam of a magneto, to effect instantaneous and efficient timing of the spark impulses, relative to the engine with which the magneto is employed.

10 20 A still further object is an improved provision for producing, and for timing the production of spark impulses in a magneto for igniting the combustible charges in the cylinder of an internal combustion engine having irregular firing sequences.

An additional object is to provide an improved magneto which is neat and compact in arrangement, is economical to construct and reliable in its operation.

25 30 Further objects and advantages will appear from the following detailed description of parts and the accompanying drawings, in which:

Fig. 1 is a side elevation, partially in section, of a preferred form of magneto to which certain of the present improvements are applied; Fig. 2 is a diagrammatical end elevation, as viewed from line 2-2 in Fig. 1; Fig. 3 is a diagrammatical showing as viewed from line 3-3 in Fig. 1, showing the timing arrangement in fully retarded position, and Fig. 4 is a diagrammatical showing as viewed from line 3-3 in Fig. 1 and shows the advanced position of certain of the timing parts.

40 45 It will, of course, be understood that the present detailed description of parts and the accompanying drawings relate to a single preferred executional embodiment of the invention and that substantial changes may be made in the described construction and ar-

angement of parts without departing from the spirit and full intended scope of the disclosure as defined by the appended claims.

Certain features of the magneto to be described are of conventional form and believed to be well known in the art, for example, the magneto constituting the particular example of the invention hereinafter described in detail, is provided with a bipolar armature continuously rotating in one direction between bipolar permanent magnets, the latter being of conventional horseshoe form. The armature, according to the present example, is of so-called high-tension type, and is constructed in the form of a metallic spool on which are wound primary and secondary coils, the arrangement being such that there occurs, twice per revolution of the armature shaft, a position at which the axis of the coils is substantially parallel to the flanks of the magneto, at which times there occurs the maximum of magnetomotive force. At these positions of the armature the primary circuit is interrupted by a breaker assembly, and the electrical impulses distributed to the ignition device in the power cylinder of the engine in the usual timed relation, and as well understood in the art.

By way of further reference to the object first set forth above, it may be noted that the older prevailing types of magneto, when driven at crank shaft speed by a four-cycle engine, produce twice the number of electrical spark impulses necessary for a single cylinder engine, each alternating impulse occurring substantially at the end of the exhaust stroke. This waste of impulses is, of course, normally without effect upon the operating cycle of the engine. It may, however, give rise to a certain inconvenience and danger during starting of the engine, since gasoline introduced into the cylinder for priming purposes, may be ignited at a time when the valves are open, thus occasionally permitting ignition of charges in the muffler and exhaust passages, frequently causing explosions and fires. Previous unsatisfactory attempts have been made to nullify this action by providing means for causing the wasted spark to take place at some point out-

55 60 65

side of the power cylinder. The present invention meets this difficulty by preventing the generation of unnecessary electrical impulses, rather than by providing means for nullifying their effects.

The construction in which a magneto having a rotating armature is prevented from generating undesirable or unnecessary igniting impulses, is of particular value in connection with multi-cylinder engines which, although operating on a uniform cycle, are required to provide electrical impulses for ignition purposes, at irregular intervals. Such a situation arises, for example, in a magneto for application to a two-cylinder four-cycle engine, in which the cylinders are arranged side by side and in which the cranks are angularly spaced at 180 degrees. In such an engine the firing impulses are separated by 180 degrees of crank shaft rotation, followed by a non-firing interval of 540 degrees. In other words, one working stroke of the engine precedes the succeeding working stroke by 180 degrees, the two working strokes being followed by two idle strokes. During each of the idle periods of the engine, the magneto armature passes positions of a high E. M. F. at which a spark impulse would be produced, if the breaker mechanism in the primary coil circuit of the magneto were permitted to function. The arrangement to be described retains the breaker assembly in open circuit, inoperative position, during the idle periods of the engine to which it is applied. It will be understood, however, that, while for convenience there is described an application to a specific engine of the type noted, the same principles and substantially the same arrangement may be employed on engines of a variety of other types, for example, two cylinder V type engines, as used on motorcycles, the example described being considered as particularly applicable to multi-cylinder internal combustion engines having a non-uniform firing sequence, due to a particular relation of cranks or cylinders.

The preceding preliminary discussion of the general principles underlying the present disclosure, has been presented to effect a better understanding of the structure and operation of the interrupting means and other operating elements of the magneto to be described. Certain other features of the present invention, for example, the means employed for advancing and retarding the timing of igniting impulses, is regarded as entirely practical of application to a magneto for use on any usual type of engine, irrespective of whether it may be employed with one or a number of power cylinders, operating on a cycle in which the ignition impulses occur regularly or irregularly.

Referring by numerals to the drawings of the particular disclosure, 10 designates, gen-

erally, a magneto of any conventional form, which includes, by preference, a frame 11 in which is mounted a permanent magnet 12 of any suitable form. An armature appears at 13, the essential features of which may be of usual form, and extending from end portions thereof are armature shafts 14 and 15. The shaft 15 may be in operative association with the crank shaft of an internal combustion engine (not shown) or with any suitable driving apparatus.

Upon an end face 16 of the armature 13 is carried, by preference, a breaker bar 17 (Fig. 2), which is fulcrumed on a pin 18 fixedly secured to the armature. An end of the bar 17 is provided with a contact point 19 which is arranged for movement relative to a contact point 20 adjustably attached to the end face of the armature. The point 20 is, by preference, insulated from the armature, but is in electric connection with the usual low tension winding (not shown) on the armature. The oscillating movement of the breaker bar 17 about its pivot pin 18, is produced by means of a rubbing block 21 which is secured to an end of the bar 17, and which follows the outer surface of a cam 22 under the influence of a spring 23. It will be apparent that by providing a suitable camming surface on the cam 22, any desired oscillating movement of the breaker bar 17 may be attained. In the present, preferred example, a pair of cam depressions 24 and 25 are provided, which are so related to the interrupting means as to cause two interruptions of the current separated by substantially 90 degrees of relative rotation between the cam and the bar 17, the remaining cam surface being substantially circular, with the axis of rotation of the shaft 14 as a center, and formed on such a radius that the points 19 and 20 are kept open during the greater part of the cycle of armature rotation, and closed only during the brief intervals when the rubbing block 21 comes opposite the low points of the cam 22. As will hereinafter appear, both the cam 22 and the breaker point assembly are normally rotated in the same direction, but at different rates.

The cam 22 is, by preference, freely rotatable on the shaft 14, being mounted on ball bearings 26. This cam is operatively driven by, and rotated relative to the armature shaft 14 in the following manner: A gear 27 is, by preference, keyed to the armature shaft 14, and meshes with a gear 28 which is rotatably mounted on a shaft 29. The gear 28 is, by preference, rigidly attached to or formed integrally with a gear 30, thereby forming a combined idler gear, which meshes with a gear 31 forming an extended portion of the rotating assembly including cam 22. In the preferred example, the gears 27 and 28 are provided with an identical number of teeth, and due to the fact

that the gears 28 and 30 rotate as a unit on the same axis, the gear 30 rotates at the same speed as the armature shaft 14. But the gear 30 is provided with a smaller number of teeth than the gear 31 with which it meshes, for example, to effect a two-to-one driving ratio, and therefore the gear 31 and cam 22 rotate, in the present instance, at half the speed of the armature shaft 14. It will be apparent that by using the combined idler gear 28-30, the speed of the cam is not only reduced to half that of the armature, but that the cam is driven in the same direction of rotation as the armature, and hence in the same direction of rotation as the breaker assembly.

It will appear from this construction that the relative speed of the cam 22 and the breaker assembly, particularly the rubbing block 21, is only a fraction of the relative speed otherwise existing between a stationary interruptor assembly and a cam rotating at armature speed, or vice versa. By this expedient, wear is minimized between the cam and the rubbing block, and, as will herein-after appear, the shape of cam 22 is such that the breaker arm 17 is actuated only at the time when an igniting impulse is useful and necessary.

As noted above, the idler gear 28-30 is rotatably mounted on the shaft 29. This shaft is fixedly secured to an arm 32 which is capable of a limited range of rotative movement, in the present showing about the same axis as the armature shaft 14. This arm is journaled in a removable end closure 33 and further cooperates with this closure to provide a journal or cage for roller bearings 34. It thus appears that the closure 33 and arm 32 coact to constitute a journal structure containing the bearing 34 and the outer end of shaft 14, besides serving in part to house the timing and breaker assembly. Upon an outer end 35 of the arm is keyed a lever 36 by means of which the arm 32 may be angularly displaced for timing purposes, with respect to the shaft 14 or armature 12. Stop lugs 37 are, by preference, adjustably secured to the frame 11, to provide means for limiting the movement of the lever 36. It will be readily seen that angular movement of the arm 32 about the shaft 14 does not disturb the mesh of the gears 27, 28, 30 and 31, but that such movement does produce a limited rotation of the compound idler 28-30, relative to the armature and gear 27, and consequently serves to rotate to a small extent, the gear 31 and cam 22. This rotary movement being imparted to the gear 31 and cam 22, the angular relationship between the cam 22 and the rubbing block 21 is altered, with the obvious effect of retarding or advancing the time of breaker point movement, for spark timing purposes.

The operation of the interruptor assembly, with particular reference to the cam 22 and

breaker arm 17, is thought to be apparent from the above description of parts and their relation, but may be briefly described for sake of completeness. Assuming a clockwise rotation of the shaft 14, cam 22, and hence the breaker assembly, all as viewed in Figs. 2, 3 and 4, a reference marker 38 is employed in Figs. 3 and 4 to indicate, in the present example, a particular angular position of the rubbing block 21. A corresponding reference marker 39 is employed to indicate a point on cam 22, such that when the rubbing block is moved angularly, relative to the cam, the coincidence of the points 38 and 39 will cause an effective actuation of the breaker points to interrupt the primary circuit of the armature after it has been previously closed by the cam, in such a manner as to cause an electrical impulse for ignition purposes. Since the cam 22 rotates at half the speed of the breaker point assembly, point 38 will move to the dotted position shown in Fig. 3, while point 39 moves to its dotted position appearing in the same figure, thus causing at the time of coincidence of points 38 and 39, an impulse producing a spark in one of the power cylinders of the engine.

It will appear from Fig. 2 that the cam 22 is provided, over the greater portion of its periphery, with a circular surface constituting a relatively high area adapted to maintain the breaker points 19 and 20 in open position. Actuation of the breaker arm first takes place to close the points, after which the subsequent high portion of cam 22 serves again to open the points, with the effect of producing a spark impulse.

Referring to the diagrams appearing in Figs. 3 and 4, the operation of the timing control may be readily followed. In Fig. 3, for the purpose of description, the arm 32 may be seen in its full retard position, with its center line substantially offset to the clockwise side of the magneto center line. In this position, the armature has a momentary position ahead of the vertical center line, as indicated by the reference marker 38. It will be readily seen that a point on the cam, by which the breaker is actuated to cause a spark impulse, is indicated by marker 39. Since the armature rotates at twice the speed of the cam, an ignition impulse will take place substantially at the point indicated by the dotted positions of the markers 38 and 39.

In Fig. 4 the timing has been changed by moving the arm 32 and its related parts, in a counterclockwise direction, relative to the vertical center line. The armature reference marker 38 still remains at the position shown in full lines in Fig. 3, but the cam, due to the gearing relation, has been moved counterclockwise with respect to the armature, as indicated by the marker 39. By permitting the normal motion of the armature to be resumed, the armature marker will overtake

the cam reference marker substantially at the point indicated by the dotted position of the markers. It will be apparent that the armature has rotated an angular distance substantially twice the corresponding angular rotation of the cam. At the position indicated in dotted lines, the interruption of the primary current causes in a well known manner, the production of a high tension ignition current. It will be readily seen from Figs. 3 and 4, that the ignition takes place earlier or more advanced, in the position shown in Fig. 4, than is the case with the timer in its full retard position, as appears in Fig. 3. That the timed relation of the spark impulse, relative to the cycle of operation of the engine, is changed by movement of the parts from their positions indicated in Fig. 3 to the position shown in Fig. 4, will be apparent from the fact that the angular relation between the position of coincidence of markers 38 and 39, and the vertical center line, is substantially less in Fig. 3, than is the corresponding angle of Fig. 4.

In order to distribute the spark impulse to the desired cylinder, a collector ring 40 is provided, which is keyed to the armature shaft 15. This ring is, by preference, provided on its periphery with a contact segment 42 and a non-conducting segment 41. The segment 42 is, by preference, in electrical connection with the armature secondary, (not shown), and is so disposed in respect to a pair of collector brushes 43 and 44 as to be in engagement with one of the brushes when a cam depression is operatively associated with the breaker bar. By this provision, the spark impulse may be distributed to the desired cylinder by means of leads 45 or 46 in the desired firing sequence.

In the preferred device described, the arrangement for varying the timing of the spark impulses, is constituted by the same novel arrangement of parts used in the production of the irregular ignition impulses. For it will be observed that the timing is attained without disturbing the meshed relation of the gearing between the interrupting means, nor the half speed trailing motion of the cam. Further, any desired degree of timing may be easily and readily effected during operation of the magneto and an associated engine. It will be understood that the described device is subject to various alterations without appreciably affecting the operating principle. For example, the cam depressions 24 and 25 may be disposed with their active points at any desired angular relation, in order to effect any desired firing sequence in multi-cylinder engines.

It will be apparent that the described device is simple and compact in arrangement, and that a minimum number of parts is used to effect an irregular firing sequence and the timing thereof. Further, the parts are read-

ily accessible for repair purposes by removal of the cover which carries the timing arm. In the present device the parts are all of a sturdy construction, and are so related that a minimum of wear occurs over an extended period of use.

I claim as my invention:

1. In a magneto having an armature adapted for unidirectional rotation, and arranged for a plurality of maxima of magnetomotive force per revolution of said armature, means including a circuit interruptor and an interruptor-actuating cam, said means being arranged for rotation coaxially with the armature, and adapted to cause interruptions of an armature circuit substantially coincident with certain of said maxima, said means adapted, through said cam and interruptor, to keep said circuit open, whereby to prevent an interruption of the armature circuit during another of said maxima.
2. In a magneto adapted for use with an engine requiring irregularly spaced ignition impulses, a circuit interrupting device including a cam, a breaker element, means for rotating said cam and said breaker element relative to each other, for actuating said breaker, a member adapted for actuating said means for timing purposes, and means constituted by said device for preventing effective actuation of said breaker element, except in synchronism with the firing periods of an engine with which the magneto is employed.
3. In combination in a bipolar magneto, a bipolar armature, circuit breaking means carried thereby a cam adapted to rotate at half the speed of said armature, for actuating said circuit breaking means, said cam having portions adapted to maintain said breaking means inoperative, and two portions adapted to operate said breaking means, said operative portions subtending an angle of 90 degrees with respect to the axis of rotation of said cam.
4. In a magneto including a rotatable armature, and an interruptor for an armature circuit, a rotatable cam disposed coaxially with respect to the armature and arranged to effect a plurality of separate movements of said interruptor during a given half revolution about its axis.
5. In a magneto, an armature, circuit-breaking means for the armature circuit arranged for rotation with said armature, and an interruptor member adapted to revolve at a speed different from the speed of the armature and adapted repeatedly to actuate said circuit-breaking means, within a given half revolution of said interruptor member.
6. In a magneto, an armature, opening and closing means for a circuit carried by said armature, and means carried by the armature and rotatable relative thereto, said last named means adapted operatively to engage the

circuit opening and closing means at irregular intervals.

7. In a magneto, a rotatable armature, means carried by the armature for interrupting the armature circuit, means, adapted to be rotated by and at a speed different from that of the armature, adapted operatively to actuate said interruptor means and a timing member adapted to move said means relative to each other.

8. In a magneto including an armature, circuit-breaking means carried by said armature, means arranged to rotate at other than armature speed, for actuating said circuit-breaking means, said circuit breaking- and actuating-means being arranged for timing movement relative to each other, independently of rotation of said armature.

9. In a magneto, circuit-bearing means for the armature circuit, a cam for actuating said circuit breaking means, said cam and breaking means being arranged for differential, unidirectional rotation, and means for varying the timed relation between said cam and circuit breaking means.

10. In a magneto, a rotatable armature assembly including a shaft, a circuit breaker and a cam for actuating said circuit breaker, said cam and circuit breaker being carried by said armature assembly, and means for rotating said cam at a speed different from that of the circuit breaker.

11. In a magneto, an armature assembly including a shaft, a circuit breaker and a cam for actuating said circuit breaker, said cam and circuit breaker being carried by said armature assembly, and means for rotating said cam at a speed different from that of the circuit breaker, said cam being constructed to maintain said breaker in open position during the major portion of revolution of the cam and to actuate said breaker only during a minor portion of such revolution.

12. In combination in a magneto, a revolving armature, circuit breaking means carried thereby, a cam member adapted to revolve at a speed other than the speed of said armature, said cam member having a plurality of relatively projecting portions adapted to be brought into operative engagement with said circuit breaking means, at irregular intervals.

13. In a magneto, an armature, circuit breaking means, a cam for actuating said circuit breaking means, a gear operatively associating said cam and breaking means, and a pivoted lever carrying said gear.

14. In a magneto, an armature, circuit breaking means carried thereby, a cam for actuating said circuit breaking means, a gear train operatively relating said armature and cam, and means for shifting the axis of one of the gears in said train.

15. In combination in a magneto, an armature, circuit breaking means carried thereby, a cam adapted to actuate said circuit breaking means, a gear train operatively associating said armature and said cam, one of the gears of said train being adapted for rotation relatively to, and about an axis of rotation of another of said gears.

ture, circuit breaking means carried thereby, a cam adapted to actuate said circuit breaking means, a gear train operatively associating said armature and said cam, one of the gears of said train being adapted for rotation relatively to, and about an axis of rotation of another of said gears.

16. In a magneto, including an armature assembly, a contact breaker, a cam, adapted for actuating said breaker and carried by the armature assembly, and a timing member adapted for movement to vary the relation between said cam and breaker assembly and constituting a journal for the armature assembly.

17. In combination in a magneto, an armature including an armature shaft, circuit breaking means carried by the armature, a cam for actuating said circuit breaking means, a gear adapted operatively to connect said circuit breaking means and cam, a pivoted arm forming an axis for said gear and constituting a journal for said armature shaft.
